UNITED STATES PATENT OFFICE.

ALBERT L. McMASTER, OF ROCHESTER, NEW HAMPSHIRE.

METHOD OF CHARTING AND CUTTING UPPER-LEATHERS.

1,264,670.

Specification of Letters Patent. Patented Apr. 30, 1918.

Application filed November 9, 1916. Serial No. 130,501.

To all whom it may concern:

Be it known that I, ALBERT L. McMASTER, a citizen of the United States, and a resident of Rochester, in the county of Strafford, and State of New Hampshire, have invented a certain new and useful Improvement in Methods of Charting and Cutting Upper-Leathers, of which the following is a specification.

10 My invention relates to an improved method in charting and cutting shoe leather and the like, and it consists in the steps and operations herein described and claimed.

15 An object of my invention is to provide an improved method whereby an animal hide may be marked or charted so that the various portions of the hide may be designated as regards quality, and a guide provided to assist in the cutting operation.

Another object of the invention is to utilize the charting of each hide in making a stencil, so as to preserve in permanent form the laying out and cutting ability of 25 individual cutters, so that such ability may be taken advantage of for the purposes of instruction and future cutting operations.

Another object of the invention is to perforate the stencil in vari-figured lines, so 30 that when the stencil is applied to a hide, the various portions of the hide will be clearly marked and constitute an index in the assorting operation.

Other objects and advantages will appear 35 from the following specification, reference being had to the accompanying drawings, in which—

Figure 1 is a plan view of a hide showing the surface thereof sub-divided into squares;

40 Fig. 2 is a plan view of a hide illustrating how it is divided into sections, the sections being numbered;

Fig. 3 is a plan view of a hide illustrating the manner of applying the patterns;

45 Fig. 4 is a plan view of a portion of a hide showing the manner in which it is stenciled, the various portions of the hide from which the patterns are to be cut, being defined by vari-figured lines;

50 Fig. 5 is a plan view of a hide illustrating how the various portions of the hide may

be indicated by colored lines, the regions designated by the colored lines being shown by solid coloring;

Fig. 6 is a plan view of a hide illustrating how the different portions of the hide may be identified by using vari-figured lines in marking the sub-divisions;

Fig. 7 is a perspective view of a number of leather cuttings, and illustrating more 60 particularly the stencil markings;

Fig. 8 is plan view of a stencil chart;

Fig. 9 is a view of a portion of the stencil chart, illustrating how the leather cuttings are reassembled thereon preparatory to 65 making a stencil;

Fig. 10 is a view of a portion of the stencil chart illustrating how the leather cuttings are outlined thereon;

Fig. 11 is a view of a portion of the stencil 70 chart, illustrating the method of perforating the outlines, and

Fig. 12 is a view of the completed stencil showing portions thereof as having been 75 perforated, and numbered, ready for filing away.

In the art of shoe manufacture, and more particularly in that branch thereof wherein animal hides are cut into upper leathers, it is a common occurrence to find that considerable amounts of leather are wasted or lost principally on account of the absence of definite guides for the cutter to follow. In carrying out my invention in the first instance, I sub-divide a hide 1 by ordinate 85 horizontal and vertical rulings 2 and 3. These rulings are preferably made with a crayon, so that they may be erased without difficulty, and are spaced approximately three inches apart. The spacing of the rulings is purely arbitrary, and may be such as will answer the requirements of any particular hide.

The next step in carrying out my invention is to accentuate certain ones of the rulings 95 2 and 3, as shown in Fig. 2, so as to divide the hide into sections that will represent the various portions thereof. These sections are invariably nine in number, and may be numbered from one to nine to aid 100 in performing other operations.

The numbered sections of the hide repre-

senting the portions thereof as regards quality, are as follows:

- 5   No. 1, left fore leg;
- " 3, right fore leg;
- " 7, left hind leg;
- " 9, right hind leg;
- " 2, head;
- " 8, butt;
- 10   " 5, center;
- " 4, left flank; and
- " 6, right flank.

In order to identify the various numbered sections of the hide just referred to, reference is directed to Fig. 2 of the drawings, in which 4 indicates the accentuated lines dividing the hide into sections.

The operation or acts just enumerated, are what I term charting the hide. It will 20 at once be apparent that the horizontal and vertical rulings on the surface of the hide form guides by which the cutter is enabled to judge distances in applying his patterns. The dividing of the hide into the nine sections previously described, separates the different qualities of the stock for the cutter, since for instance, the best portion of the hide is in the center, marked number 5, while the portions of poorer quality are in 30 the sections marked numbers 1, 2, etc. The hide having been charted in the manner set forth, is given to a cutter whose duty it is to cut the hide into the greatest number of upper leathers possible. The ability of a cutter rests entirely on his experience and the manner in which he applies the cutting patterns to the hide. Instead of the present uncertain method of cutting haphazard into a skin, the cutter has definite lines before 40 him which, as stated above, separate different qualities of stock in that skin and at the same time furnish a definite known spacing in squares which provide a constant means for judging distances.

45   To illustrate the importance of this advantage, an ordinary cutter can cut one hundred pairs a day, and as a rough estimate, there are ten pieces to a pair. This means that the cutter must go through the operation of laying a die or pattern on his stock one thousand times a day. Another advantage of charting the leather hide in the manner explained is that, on employing a new, untried cutter, charted stock may be given 50 him to be cut. His skins may be reassembled in order to ascertain his method of procedure, and his ability thus proven at once.

55   If, instead of charting the hide by means of the ordinary rulings 2 and 3, and the 60 accentuated lines 4, it be found practical to employ some other method, the lines of the various sections of the hide may be designated by different colors. In Fig. 5 of

the drawings I have illustrated a hide on which the various portions thereof are distinguished by such colorings, the color scheme being as follows:

- Head, #2, yellow,
- Legs, #1, 3, 7, 9, red,
- Flanks, #4, 6, white,
- Center, #5, blue,
- Butt, #8, brown.

The colors, as they are listed above, on the different parts of the hide, always remain the same. That is to say, legs are always red, etc., no matter what the stock is. By reference to Fig. 6, it will be observed that I may employ still another method of identifying the different portions of the 80 hide. In this instance the ordinary rulings represented by 2 and 3 in Fig. 1 of the drawings, are made of vari-figured lines. These lines 2 and 3, are composed of symbols as follows:

- Head, diamonds,
- Legs, squares,
- Butt, dot and dash;
- Center, circles,
- Flanks, triangles,

It will readily be understood that shoe upper leathers cut from a hide or hides having the sections thereof colored or marked by symbols to indicate the various portions, 95 according to the quality thereof, may readily be recognized and assorted.

It is a fact that five different cutters, if given the same pattern and stock, would undoubtedly use different methods or runs 100 in cutting their individual lots. One cutter might possess some point of advantage in laying on his patterns which, by the aid of the chart, could readily be detected. It is also a fact that new combinations of patterns are continually confronting the foreman of a cutting room. In order to preserve the various features of merit displayed in the manner of applying the patterns and cutting the stock of individual 110 cutters, it becomes desirable to form a permanent record by means of stencils.

Let it be assumed that it is desired to form a stencil pattern of the method of cutting stock, of one particular cutter. A stencil 115 chart 5 is provided, which may be a sheet of oil board, zinc, copper, or any suitable material of which a stencil may be made. The stencil sheet 5 is provided with ordinary rulings 6 and 7, these being arranged horizontally and vertically, identical with the rulings 2 and 3 on the hide 1 illustrated in Fig. 1. A cut-up hide is now reassembled on the surface of the stencil sheet 5 in the manner represented in Fig. 9. The reassembly 120 of the portions of the hide is assisted by

the numbering on the hide and the rulings thereon, it being a simpler matter to arrange the portions so that the rulings will coincide.

- 5 The portions of the hide having been reassembled on the surface of the stencil sheet 5, the outlines of the shoe uppers 8 and tongues 9 are marked directly on the stencil sheet 5 by any suitable means, such as a pencil, these outlines or markings being indicated in Fig. 10.

Certain ones of the lines or rulings 6 and 7 are now accentuated in a manner such as employed in marking the hides shown in 15 Fig. 2, so as to indicate the various portions of the hide.

The outlines of the various portions of the shoe are now perforated by means of a suitable perforating instrument. It will be observed that, in perforating these outlines, a 20 similar identifying means is employed to identify the various portions of the hide, as in Figs. 5 and 6.

In the present instance, instead of coloring the different portions of the hide or subdividing the surface of the hide by vari-figured lines, the outlines of the portions of the shoe are perforated in various symbols in accordance with that portion of the hide 30 on which the outlines of the portions of the shoe are located.

By reference to Fig. 11, it will be observed that the perforating operation has been commenced, the symbols used being as follows:

- 35 Legs, square perforations;
Head, diamond perforations;
Center, circular perforations; etc.

Upon the completion of the perforation of 40 the outlines of the shoe portions on the sheet 5, a stencil sheet will have been created. The next act is to cut up or divide the stencil sheet 5, into sections of a convenient size for filing away for future reference and use.

45 By reference to Fig. 12 it will be observed that the stencil sheet has been cut up into sections approximately twelve inches square, and for convenience in reassembling, has been numbered, 1, 2, 3, etc., these sections being indicated at 10.

Upon occasion to use the stencil prepared in the manner above explained, the various stencil sections 10 are reassembled according to number, in a suitable stencil frame. The 55 stencils are then laid upon a hide which it is desired to chart, and a suitable, easily erased ink is applied thereto, thus transferring the design of the stencil onto the leather in vari-figured outlines. The result is partially pictured in Fig. 4, in which the various portions of the hide, as regards quality, will readily be recognized by the symbols of which the lines are composed, even by dis-

regarding the rulings 2 and 3 and the accentuated lines. The hide prepared in this 65 manner is now given to a cutter, who proceeds to cut out the outlined portions. The result is that illustrated in Fig. 7, from which it will be observed that the edges of the uppers and tongues 8 and 9 respectively, 70 are marked with various symbols representing those portions of the hide from which they were cut. The work of assorting the various portions of the shoe now becomes comparatively easy, since the symbols on the 75 edges of the cut leather are an index to the grade of the leather of which the cuttings are made.

While this method of charting and stenciling is primarily intended for shoe leather, 80 it is obvious that it may readily be adapted in marking sole leather, cloth, rubber, and the like.

I claim:—

1. The method of charting a hide, consisting of marking the hide into major sections to designate the portions containing leather of different qualities, and marking patterns upon the hide surface with lines having figured components, the figure components of said lines being the same if traced on major sections of the same quality, but different if on major sections of different qualities. 85 90

2. The method of charting a hide, consisting of marking the hide into major sections to designate the center, legs, flanks, head and butt containing leather of different grades, and applying a marking on the surfaces of the sections thus designated for purposes of future distinction. 95 100

3. The method of charting a hide, consisting of marking the hide into major sections to designate the center, legs, flanks, head and butt containing leather of different grades, 105 and stamping the surfaces of corresponding sections with corresponding devices for purposes of future distinction.

4. The method of charting a hide, consisting of dividing the surface by crossed rulings, accentuating certain of the rulings to designate major sections indicating the center, legs, flanks, head and butt containing different grades of leather, and applying a distinguishing medium to the designated 110 115 sections so that like grades of leather may be recognized after having been cut up.

5. The method of preparing a hide stencil chart, consisting of marking a hide into major sections to designate the grades of 120 leather, applying the patterns and marking the outlines thereof on the hide, cutting the hide, re-assembling the cuttings on a chart having facsimile major section markings, outlining the cuttings on the chart, and perforating the outlines with perforations hav- 125

ing vari-figured components, the figure components of said perforations being the same if formed on major sections of the same quality, but different if on major sections of different qualities.

6. The method of charting, consisting of sub-dividing the surface by crossed rulings, accentuating certain ones of the rulings to form sections, laying on the pattern, cutting the hide, reassembling the cuttings on a stencil chart having rulings corresponding to those on the hide cuttings, marking the outlines of the cuttings, designating the sections on the stencil, and perforating the outlines in accordance with the sections.

7. The method of preparing charting stencils, consisting of sub-dividing the surface of a hide by crossed rulings, accentuating certain ones of the rulings to form sections, laying on the pattern, cutting the hide, reassembling the cuttings on a stencil chart having crossed rulings corresponding to those on the hide cuttings, marking the outlines of the cuttings, designating the sections on the stencil, and perforating the outlines with vari-figured symbols in accordance with the representative sections.

8. The method of charting, consisting of sub-dividing a hide surface by crossed rulings, accentuating certain ones of the rulings to form sections, numbering the sections to facilitate re-assembly, laying on the pattern, cutting the hide in accordance with the pattern, re-assembling the cut sections according to numbers thereon, on a stencil chart having rulings corresponding with those on the hide, marking the outlines of the cuttings on the chart, removing the cuttings, and designating sections of the stencil chart to correspond with the numbers on previously superposed cut hide sections.

9. The herein described method which consists in charting the surface of the skin to be cut, to permit of ready reassembling of its cut portions, reassembling the cut portions on a charted surface corresponding to the charted surface of the skin, and marking upon the latter charted surface the outlines of the skin cuttings, for the purpose described.

ALBERT L. McMASTER.
